LEVEL

Harry L. Smith, Hiway 57 N., Oakland City, Ind.
Filed May 12, 1961, Ser. No. 109,642
1 Claim. (Cl. 33—213)

This invention relates to a level, and has as its primary object the provision of an improved level which will establish a predetermined desired angle, and which may be set at that angle in the construction of rafters, for roofing, in the digging of ditches having a desired angle of inclination, or at any other occupation wherein it is desired to measure and maintain a particular angular relation with a level surface.

A further object of the invention is the provision of a device of this character which may be so constructed that a level angle may be predetermined by means of a protractor scale in the exterior of the level, and when the angle is obtained the protractor is secured in position, and so arranged that when the article is moved, the predetermined angle may be remeasured in any other remote locality.

Still another object of the invention is the provision of a device of this character which is sturdy and durable in construction, reliable and efficient in operation, and relatively simple and inexpensive to manufacture, assemble, and utilize.

Other objects reside in the combinations of elements, arrangements of parts, and features of construction, all as will be more fully pointed out hereinafter and shown in the accompanying drawing wherein there is disclosed a preferred embodiment of this inventive concept.

In the drawing:

FIGURE 1 is a front perspective view of one form of level embodying elements of the instant invention.

FIGURE 2 is an enlarged sectional view taken substantially along the line 2—2 of FIG. 1 as viewed in the direction indicated by the arrows.

FIGURE 3 is a sectional view taken substantially along the line 3—3 of FIG. 2 as viewed in the direction indicated by the arrows; and

FIGURE 4 is an enlarged fragmentary view of the level shown as set at a desired angle relative to a flat surface.

Similar reference characters refer to similar parts throughout the several views of the drawings.

Having reference now to the drawings in detail, the level of the instant invention is generally indicated at 10 and comprises an elongated member 11 having a flat level surface 12 on the underside thereof. The device is provided with a central section 13, which is provided with a transversely extending cylindrical bore 14 extending entirely therethrough.

Interiorly of the bore 14 there is positioned a ring or annulus 15 having an internal shoulder 16. The annulus 15 is provided with a groove 17 adjacent one face thereof in which is set a glass panel or pane 18. Pane 18 is held in position by an annular ring 19 having a central opening 20 therein, as by means of screws 21 which extend through suitable spaced openings in ring 19 and into appropriate bores 22 in the rim of annulus 15.

Seating on the shoulder 16 is the bore 23 of a generally circular ring 24, having an internally positioned substantially U-shaped frame forming shoulders 25, across which extends a conventional bubble level 27 having its ends inset in the shoulders. The level 27 is provided with the usual leveling marks 28 and contains the customary interior bubble 29. The member 24 includes an integral ring 30 which seats in a groove or channel 31 in the face of annulus 15, and is closed by a glass pane 32 which is held in position by means of a ring 33 similar to the previously described ring 19, and screws 34 which extend

2

into suitable bores 35 in annulus 15. In order to provide for fine adjustment of the bubble level 27 elongated arcuate grooves 36 are cut into the rim 30 so that the entire level assembly including the shoulders 25 and the associated level 27 may be minutely varied to accommodate for changes in temperature, wear, or other conditions.

Attached to the ring 33 is a pointer 37 which is held in position by one of the screws 34 and positioned about the exterior of plate 33 in an arcuate protractor scale 40 which is marked off in degrees. The arrangement is thus such that both rings 33 and 19 are rotatable together with annular ring 15, and by their rotation vary the level of the internally positioned bubble level 27. Thus the pointer 37 may be set to any desired angle of inclination, and when the bottom surface 12 is positioned on a flat surface 41, as seen in FIG. 4, the angularity of the level 10 is varied until the bubble 29 is centered in the bubble level 27, then the angle indicated by the arrow 42 in FIG. 4 will be identical to the angle indicated by the arrow 43 which is the angle measured on the protractor scale 40.

In order to hold the annulus 15 in a desired position of adjustment a set screw 45 having a head 46 extends through a threaded bore 47 in a bushing 48 which is provided with a flange 49, the flange seating in an opening 50 interiorly of the level, and the bushing 48 extending through an appropriate bore to the top edge 51 thereof. Obviously, tightening of the head 46 will serve to tighten the screw 45 so that its point 52 engages the annulus 15 and securely holds the same in any desired position of adjustment.

Rotation of the annulus 15 is facilitated by a pair of protuberances or knobs 55 which are suitably screwed into the surface of ring 33 on opposite sides thereof so that the entire assembly may be moved with a minimum of effort and difficulty.

From the foregoing it will now be seen that there is herein provided an improved level which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

I claim:

In a level, in combination, an elongated flat surfaced member having a central bore therethrough, an annulus mounted for rotation in said bore, a bubble level extending transversely across said annulus, a protractor scale on said member around said bore, a pointer on said annulus for indicating angularity on said scale, said annulus having a transparent pane at each open end thereof, a flat ring at each end holding said annulus in said bore and said panes in said annulus, said annulus containing a U-shaped frame having legs forming spaced parallel shoulders and having a ring integrally associated therewith, the ends of said bubble level being inset in the shoulders of said U-shaped frame, operating handles associated with said annulus for facilitating rotation thereof, and means comprising arcuate grooves formed in said ring adjacent its periphery and screws extending through said flat rings into said grooves permitting rotation of said U-shaped frame relative to said annulus to adjust said bubble level.

CERTIFICATE OF CORRECTION

Patent No. 3,069,782

December 25, 1962

Harry I. Smith

It is hereby certified that error appears in the above numbered patent requiring correction and that the said Letters Patent should read as corrected below.

In the grant, lines 1 and 12, and in the heading to the printed specification, line 3, for "Harry L. Smith" read -- Harry I. Smith --.

Signed and sealed this 7th day of November 1967.
